FIG. IV

FIG. V

FIG. VI

FIG. VII

INVENTOR
MANUEL H. RODRIGUES

BY *Manuel H. Rodrigues*
ATTY'S

UNITED STATES PATENT OFFICE.

MANUEL H. RODRIGUES, OF HONOLULU, TERRITORY OF HAWAII, ASSIGNOR OF ONE-HALF TO JOHN J. PAVAO, OF HONOLULU, TERRITORY OF HAWAII.

TIME SWITCH.

Application filed October 27, 1924. Serial No. 746,197.

The present invention relates to improvements in electric alarm clocks, and its principal object is to provide means allowing an alarm clock to close an electric circuit at a predetermined time, to open the electric circuit at a predetermined later time, and to intermittently close and open the circuit during the interval. My invention might be particularly used, for instance, where it is desired to intermittently light a show window or an advertising scheme for a certain length of time without necessitating the presence of an operator. If it is desired to have the lights going intermittently in a show window between 9 and 12 in the evening, and the operator leaves the store at 5 o'clock, he may set the alarm clock to close the circuit at 9 and to open the circuit at 12 while the working mechanism of the alarm clock will automatically effect the intermittent opening and closing of the circuit during the hours from 9 to 12. My invention constitutes an improvement on the device described by me in my copending application Serial No. 692,141, filed February 11th, 1924, and contemplates to utilize two alarm releases in an ordinary alarm clock for effecting the closing and opening of the circuit at the predetermined times and to utilize the escapement control of the clock mechanism for the intermittent opening and closing of the circuit. Further objects and advantages of my device will appear as the specification proceeds. The preferred form of the invention is illustrated in the accompanying drawings in which

Figure 1 shows a front view of my alarm device with a box enclosing the same.

Figure 2 a rear view of the same device.

Figure 3 a front view of the operating mechanism of the alarm device, the dial and the hands of the clock mechanism being removed.

Figure 4 a vertical section through the box illustrating the general wiring scheme.

Figure 5 an end view of the box.

Figure 6 a diagrammatic illustration of the operation and coaction of the different units, and

Figure 7 an end view of the mechanism shown in Figure 3.

While I have shown only the preferred form of the invention, it should be understood that modifications may be made within the scope of the claim hereto attached

without departing from the spirit of the invention.

My alarm device 1 is preferably mounted in a suitable box or casing 2 presenting a front wall 3, a rear wall 4 and end walls 6. The front wall is provided with an opening 5 allowing the dial 7 of the clock mechanism to be viewed therethrough and the rear wall is preferably provided with a door 8 allowing of access to the rear of the working mechanism for setting the various adjustable elements.

The mechanism, as such, includes the well known conventional elements of the ordinary alarm clock which may be briefly described as follows:

A spring operated wheel 9 imparts rotary motion to the shaft 11 on which the minute hand 12 is mounted. A smaller pinion 13 drives a larger gear wheel 14 mounted coaxially with a pinion 16 which latter drives the gear wheel 17 formed integral with a sleeve 18 to which latter the hour hand 19 is secured so that the latter is revolved in the well known speed ratio relative to the minute hand. The pinion 16 also revolves the two gear wheels 20 and 21, rotatable on the two shafts 22 and 23. The latter shafts have hands 24 mounted thereon and have also small lateral projections 26 extending therefrom which latter normally ride on the end faces of sleeves 27 formed integral with the gear wheels 20 and 21 respectively and thereby push the latter gear wheels inwardly against the springs 28 and 29 until the gear wheels have turned sufficiently far to bring a notch 31 into registry with the projections 26 whereupon the gear wheels are allowed to jump forward under the action of the spring 28 or 29 respectively. The two springs which are fastened at one end to the front plate 32 of the clock mechanism, as shown at 33, are bent at their extreme ends 34 to present lips 36 projecting over one of the edges of the plate 32, which latter lips are used for the operation of my movable contacts as will appear later in the description.

The main shaft 11 carrying the minute hand 19 has a large gear wheel 37 fixed thereto which latter drives through a pinion 38, a shaft 39 which latter transmits rotary motion through a gear wheel 41 and a pinion 42 to a shaft 43. The latter has a gear wheel 44 mounted thereon driving the

escapement wheel 46 which latter is well known in the art and, therefore, not further illustrated. The only portion of the mechanism constituting the escapement control 5 that I utilize for the purpose of my invention, is the shaft 39 on which I mount a toothed wheel 47 for the purpose of operating a lever mechanism for effecting the intermittent opening and closing of my circuit.

10 All the mechanism thus far described is substantially known in the art and not claimed in the present invention.

The general object of my invention being to cause the clock mechanism to open and 15 close an electric circuit in accordance with predetermined rules, the main portion of my improvement is the switch operated by the clock mechanism. For this purpose I provide an extension plate 48 of insulating material secured to the rear plate of my clock mechanism in any suitable manner as by strips 49 and mounted thereon a stationary contact 51 having a tongue 52 extending therefrom, and having a second plate 53 20 mounted thereon with freedom of sliding adjustment which latter plate is formed with a tongue 54 so that the two tongues 52 and 54 form my two stationary contacts and are electrically connected with one another. I 25 further provide two movable contacts 56 and 57, the former being secured to the insulating block 58 and the latter to the insulating block 59, the two contacts being connected to the wires 61 and 62 respectively, 30 which latter form part of a circuit which may contain a suitable source of electrical energy and any suitable alarm device. When the contact 56 touches the contact 54 and the contact 57 touches the contact 52 the circuit is closed, but, when either 35 of these contacts become disengaged, the circuit is open.

The insulating block 58 is pivoted between the two plates constituting the main frame 45 of the clock mechanism, as shown at 63, and is normally acted on by the spring 64 to disengage the contact 56 from the contact 54, but the two contacts may be manually engaged by operating a pin 66 extending 50 through a slot 67 in the insulating plate 48 and may be held in the switch closing position by the lip 36 projecting over the edge of the front plate and engaging a projection 68 extending from the insulating block 58. 55 In this connection, it should be remembered that the lip 36 extends into an operative position for holding the projection 68 only so long as the spring 29 is forced against the front plate 32 but becomes free when the 60 spring jumps forward due to the fact that the notch 31 has reached the projection 26.

The insulating block 59 is pivoted, as shown at 69, and a coil spring 71 tends to force the contact 57 upon the contact 52.

65 These two contacts may, however, be man-

ually separated by the operation of the slide 72 secured to a pin 73 riding in a slot 74 in the plate 48. A nut 76 threaded on the pin 73 holds the latter and the slide in any desired position. One end of the slide is 75 formed with a projection 77 adapted to engage with the reduced end 78 of the insulating block 59 for pushing the latter sideways whereby the contact 57 is separated from the contact 52 and whereby the projection 79 rising from the insulating block is brought into operative relation to the lip 36 of the spring 28 so that the insulating block is locked in said position by the lip 36 as long as the spring 28 is pressed against the front plate by the alarm release mechanism. It will thus be seen that the contact 56 has a tendency to separate from the contact 54, but may be manually engaged with the same and locked in such engagement by the lip 36 on the spring 29 until such time as the release mechanism for the latter spring becomes active while the contact 57 normally tends to engage with the contact 52 but may be manually separated therefrom and locked in a separating position by the lip 36 of the spring 28 until such time as the release mechanism for the latter spring becomes active.

Means are thus provided allowing an operator to set the alarm clock to close the circuit at a predetermined time and to also open it at a predetermined later time, but it is further proposed to provide means for allowing the clock mechanism to intermittently operate one of the movable contacts for intermittently opening and closing the circuit during the interval. For this purpose I utilize the escapement control of the clock mechanism and particularly the toothed wheel 47 which bears on the free end of a bar 81 pivoted at its other end, as shown at 82, and connected through a link 83 with one arm 84 of a bell crank lever 86 pivotally supported as at 87. The other arm 88 of a bell crank lever operates a rod 89 having a stop 91 mounted thereon with freedom of adjustment and the latter bears on the reduced end 78 of the insulating block 59, a strong spring 92 operating on the arm 88 to separate the contact 57 from the contact 52. It should be noted that the spring 92 is stronger than the spring 71 tending to effect engagement between the contacts 52 and 57 while the spring 92 tends to separate the contact 57 from the contact 52. The teeth on the wheel 47 intermittently bear upon a slanting face 93 of the bar 81 for rocking the bell crank lever 86 through the link 83 and for pulling the rod 89 to the left, as viewed in Figure 2 so as to free the insulating block 59 from the stop 91 on the rod and to allow the spring 71 to force the contact 57 upon the contact 52.

The feature of intermittent opening and closing of the circuit may be eliminated by means of the handle 94 pivoted as at 96 and provided with a pin 97 bearing against the inner face of the arm 88 of the bell crank lever for pushing the latter arm upwardly, friction being relied upon for holding the handle 94 in the position desired by the operator. It will be readily seen that when the handle 94 is pushed upwardly, the pin 97 pushes the arm 88 to the left, as viewed in Figure 2 and thereby frees the block 59 from the stop 91 altogether.

The operation of my device is as follows: According to the clock shown in Figure 1, it is 8 o'clock. The operator desires to have the light system start at 9 o'clock and stop at 12. For this purpose, he first sets the upper alarm handle 24 at 8 o'clock which means that the spring 29 is released. Next he engages the contact 56 with the contact 54 by manipulating the pin 66, and he locks the contacts in engagement by moving the handle of the upper alarm dial to 12 o'clock, that is, to the time at which he wants the operation to stop. Turning the handle 24 causes the spring 29 to be pressed against the front plate and causes the lip 36 extending from the said spring to engage with the projection 68 on the insulating block 58. Next he proceeds in a similar manner with the lower movable contact, first setting the lower alarm handle 24 at 8 o'clock so as to free the spring 28. He then moves the slide 72 to the extreme right, as viewed in Figure 3, whereby the contact 57 is separated from the contact 52 and whereby the projection 79 on the insulating block 59 is brought into

operative relation to the lip 36 of the spring 28 so that the two may interlock as soon as 40 the spring 28 is forced upon the front plate by turning the hand 24 of the lower alarm to 9 o'clock, that is, to the time at which the operator wishes the operations to begin.

If the operator desires steady operation 45 during the three hours, he works the handle 94 to push the arm 88 of the bell crank lever 86 to the left, as viewed in Figures 3, but if he wishes the operation to be intermittent, that is, if he wishes the light to go on and 50 off at intervals, he pushes the handle 94 downwardly so as to allow the spring 92 to become active and to push the rod 89 to the right, whereby the contact 57 is again separated from the contact 52 while the teeth 55 on the wheel 47 intermittently overcome the action of the spring 92 and free the insulator 59 from the stop 91 thereby allowing the spring 71 to temporarily force the contact 57 upon the contact 52. A small light 95 may 60 be provided to light up the interior of the box.

I claim:

In a device of the type described, a switch having a movable contact, an escapement device for a clock mechanism, a pivoted lever, a link extending from one end of the lever and engaging said contact for pushing the same in circuit-opening position and for releasing the same, an operative connection between the escapement and the other end of the lever for intermittently operating said pivoted lever, and manually operated means for rendering the bell crank lever inactive.

MANUEL H. RODRIGUES.
